UNITED STATES PATENT OFFICE.

MARTIN NESS, OF SILVERDALE, WASHINGTON.

ATTACHMENT FOR PLOWS.

Application filed May 13, 1924. Serial No. 713,084.

This invention relates to plows and its object is the provision of a plow attachment which is adapted to be utilized for removing roots, sage-brush, or the like from ground which is broken by the plow.

More specific objects and advantages of the invention will appear in the following description.

The invention consists in the novel construction, adaptation and combination of parts hereinafter described and claimed.

In the accompanying drawings,—

Figure 1 is a side elevation of a plow with devices embodying my invention applied thereto; Fig. 2 is a plan view of Fig. 1; Fig. 3 is a detail sectional view taken substantially on line 3—3 of Fig. 1; and Fig. 4 is a detail sectional view on lines 4—4 of Figs. 1 and 2.

In said drawing, the reference numeral 5 represents, generally, a plow having handles 6, a beam 7, a share 8 and a mold-board 9 which may be of any known or suitable form or construction.

According to the present invention, at the off side of the plow beam 7 there is employed a bar 10, hereinafter designated as the frame, which is formed or bent as at 11 and 12 to provide a transversely arranged portion 13 intermediate rearwardly extending arm element 14 and shank 15 element of the frame.

The shank 15 of said frame extends through a bearing box 16 which is secured to the plow beam 7 as by means of bolts 17 and 18 passing through selected holes as at 17¹ and 18¹ of flange elements 19 of the box and a companion plate 20 disposed at the opposite side of the beam from said box. The holes 17¹ and 18¹ above mentioned are disposed preferably along arcs of circles as shown in Fig. 1 so as to most advantageously accommodate the bolts when changing the longitudinal vertical angle of the frame with respect to the beam.

As shown, the frame 10 is secured against longitudinal displacement to said box by means of set collars 21 provided on the frame shank 15 to abut against opposite ends of the box.

It is necessary sometimes to rock the frame about the plow beam on a longitudinal axis and to accomplish the same I provide a set screw 22 extending into said box to engage the frame shank.

23 represents a disk or spider having a rim element 24 and a hub element 25 which are apertured to receive a plurality of radially disposed rods or teeth elements 26 whose outer ends are preferably curved as 60 at 27, Fig. 2.

These teeth are removably secured to said spider as by means of set screws 28. The combined spider and rods constitute a wheel which is rotatably mounted on the spindle 65 element 29 of a stub axle 30, between a fixed collar 31 of the latter and a set collar 32 which is secured to the spindle element 29. Said axle is bifurcated to embrace the arm 14 and to which the axle is secured by 70 clamping the axle to the arm through the instrumentality of a screw bolt 33 engaging the bifurcations 34 of the axle. 35 represents a set screw acting supplementary to the bolt 33 for securing the axle to said arm. 75 As shown in Fig. 2, the end of the arm 14 is curved as at 36 thereby enabling the angle of the wheel 23 with respect to the plow to be changed by suitably shifting the axle lengthwise of the arm.

For use, the device is adjusted to have the toothed wheel disposed to one side of the plow beam and in front of the mold-board to enable the wheel to operate in the furrow next to that in which the plow is 85 breaking ground. The wheel, furthermore, is arranged in substantially the angular relation with the plow beam shown in Fig. 2.

As the plow is drawn along by a team or otherwise the wheel is caused to rotate, 90 whereupon the revolving teeth serve to extract fragments of roots, brush, etc., and deliver the same over a plowed trench after the latter has been filled with soil through the instrumentality of the mold-board of 95 the plow.

What I claim, is,—

The combination with a plow, of a frame consisting of a bar formed to provide a shank element and an arm element disposed 100

in substantially parallel relation with each other, one end of said arm being curved, a wheel provided with a plurality of radiating teeth elements, an axle for said wheel, said axle being mounted upon the curved end of said frame arm, means for securing said axle in adjusted positions upon said arm, a bearing box for the shank ele-

ment, means to secure said frame in adjusted positions to said box, and means for securing said box to the plow-beam for regulating the angular relation of the frame from a horizontal plane. 10

Signed at Seattle, Washington, this 9th day of April, 1924.

MARTIN NESS.
